US0D1064276S

(12) **United States Design Patent** (10) **Patent No.:** **US D1,064,276 S**
(45) **Date of Patent:** **** Feb. 25, 2025**

(54) **RESPIRATOR FILTER CARTRIDGE**

(71) Applicant: **3M INNOVATIVE PROPERTIES COMPANY**, St. Paul, MN (US)

(72) Inventors: **Jennifer A. Chaisson**, Kemptville (CA); **Jamie V. Blair**, Nepean (CA); **Gary E. Dwyer**, Mallorytown (CA)

(73) Assignee: **3M Innovative Properties Company**, St. Paul, MN (US)

(**) Term: **15 Years**

(21) Appl. No.: **29/869,926**

(22) Filed: **Jan. 12, 2023**

Related U.S. Application Data

(62) Division of application No. 29/789,824, filed on Oct. 20, 2021, now abandoned, which is a division of application No. 29/667,253, filed on Oct. 19, 2018, now Pat. No. Des. 936,226.

Primary Examiner — Rhea Shields

(57) **CLAIM**

The ornamental design for a respirator filter cartridge as shown and described.

DESCRIPTION

FIG. 1 is a perspective view for a respirator filter cartridge, showing our new design;

FIG. 2 is a front view thereof;

FIG. 3 is a rear view thereof;

FIG. 4 is a bottom view thereof;

FIG. 5 is a top view thereof;

FIG. 6 is a left side view thereof; and,

FIG. 7 is a right side view thereof.

In the drawings, the broken lines are for the purpose of illustrating portions of the respirator filter cartridge that form no part of the claimed design.

1 Claim, 7 Drawing Sheets
